PROCESS FOR CHARGING HORIZONTAL
ZINC RETORTS

Emil J. Bruderlin, Amarillo, Tex., assignor to
American Smelting and Refining Company,
New York, N. Y., a corporation of New Jersey

Application August 28, 1948, Serial No. 66,617

4 Claims. (Cl. 214—152)

1

This invention relates to the horizontal retort process for reducing zinc ores and more particularly to the manner of charging the retorts, for which operation the invention provides decided improvements.

The conventional, commercial method of charging horizontal zinc retorts by shovelling the charge into the retorts is notoriously, though by necessity, a hot, disagreeable job—in fact, it has been difficult for more than a generation for horizontal retort zinc smelters to secure and maintain adequate charger personnel for that reason. Such state of affairs is alleviated by the new charging process of the invention.

As will be apparent as the description proceeds, the process of the present invention affords many advantages in horizontal zinc retort practice, among the more important of which are:

(a) *Safety of the charger.*—When charging by the old, conventional method, the charger must necessarily stand next to the furnace where he is exposed to possible severe injury from burns occasioned by blow-outs. With the new process, the charger performs his duties a safe distance away from the furnace.

(b) *Uniformity of charge throughout all retorts in the block.*—The new process eliminates the variations encountered when charging by the old method due to such factors as tiring of the charger resulting in the latter retorts being more poorly charged, the difficulty in reaching the retorts in the upper and lower rows as compared to those in the intermediate rows, etc.

(c) *Ease of charging.*—By the new process, a charger can readily charge three or four times the number of retorts per shift that he can by the old method.

(d) *Density of charge.*—An increase in density of charge by the new process, amounting to 10% and as high as 18.5% in some instances, has been conclusively demonstrated in plant scale operations.

(e) *Greater direct metal recovery.*—It has been found that in charging the retorts by the new process, less blue powder is formed and the direct metal recovery increased by approximately 2.5% to 3%.

Although the novel features which are believed to be characteristic of this invention will be

particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a side view of an overhead feeding device and charging machine for practicing the process of the invention, looking toward the face of a horizontal retort zinc furnace,

Fig. 2 is a top view of the machine shown in Fig. 1,

Fig. 3 is a section through such machine taken on the line 3—3 of Fig. 2,

Fig. 4 is an end view of the machine and showing the furnace and retorts in cross-section, and

Fig. 5 is a cross-section of the air inlet end of one of the blow guns of the machine taken on the line 5—5 of Fig. 1.

Like reference characters denote like parts in the several figures of the drawings.

Referring to the drawings, 10 is a zinc reduction furnace comprising a bank of four tiers of horizontal retorts 12 and having a track 14 extending along the face of the furnace on which the charging machine 16 is mounted. An overhead feeding device comprising a belt conveyor 18 and tripper discharge device 20 equipped with a spout 22, is provided for delivering charge to the machine 16 at any desired station of the latter along track 14.

The charging machine 16 comprises a housing 24 enclosing an endless, bucket elevator 26 driven by a motor 28, the top of the housing 24 forming a hopper 30 adapted for registry with spout 22 of feed discharge device 20. A blow box 32, which extends vertically along housing 24 with its upper end in open communication with hopper 30, is provided with four blow guns 34 and supports air manifold 36 to which is connected flexible, compressed air supply pipe 38.

As will be seen from Fig. 5, each of the blow guns 34 is provided at one end with a compressed air inlet pipe 40 secured in position with respect to Venturi-like orifice 42 in the barrel of the blow gun by bracket 44 and set screw 46, the air inlet pipe 40 being connected with air manifold 36 and provided with a control valve 48. A series of alternating baffles 50 are provided within

the blow box 32, as shown in Fig. 3 which direct charge from the hopper 30 across the top of the blow guns 34, the barrels of which are cut away on their top portions, as shown in Figs. 4 and 5, to provide charge openings or inlet ports 52. A lowermost baffle 51 is provided in the blow box 32 for directing any charge in excess of that entering the blow guns 34 into the lower portion of housing 24 via port 53. A plurality of inspection and air inlet openings 54 are provided in a wall of the blow box 32 as shown in Fig. 2 and the whole blow box assembly is adjustable vertically by means of a hand wheel 56 operating through reduction worm 58 on hinged support 60 keyed to shaft 62.

At the end of the machine opposite the blow box assembly, there is provided a clean up or auxiliary charge hopper 64 and belt feeder 66, the latter being driven by a motor 68 and discharging into the bucket elevator 26 via hopper 70 in housing 24. An open inspection door 72 is provided in the side of housing 24 farthest away from the face of the furnace, on which side is also located an electric control switch, generally indicated by 74, for the elevator 26 and belt feeder 66, and a master electric control switch generally indicated by 76, for the elevator and feeder aforesaid and for the overhead feeding device which supplies charge via spout 22 to the charging machine hopper 30. The wiring details of such electric controls being conventional, same are omitted from the drawing, the positions of switches 74, 76 being shown to illustrate how they, with the air control valves 48, result in all of the control equipment being within easy reach of the operator. As illustrated, the charging machine is supported by a carriage comprising frame 78 and four flanged wheels 80 which serve to mount the machine on the track 14. Means for advancing the machine along track 14 may appropriately take the form of a fulcrum unit 82 (Fig. 2) manually operated with a bar.

The following will serve to illustrate one manner of charging a horizontal retort, zinc furnace using the process of the invention. The machine 16 is positioned on track 14 at the head end of the furnace 10 and the blow guns 34 aligned with the first row of retorts 12 at that end of the furnace, vertical and horizontal adjustment of the blow guns being accomplished by proper manipulation of hand wheel 56 and fulcrum unit 82, respectively. The charge (zinc sinter and reduction fuel) for the retorts is delivered by belt 18 via tripper device 20 and spout 22 to hopper 30 and thence downwardly through blow box 32 where it is deflected from side to side over inlet ports 52 by baffles 50.

As the charge passes downwardly through the blow box, valve 48 of the top blow gun (Fig. 4) is opened thereby releasing air under pressure of say, 80-100 lbs. per square inch, from manifold 36, through air inlet pipe 40 into orifice 42 (Fig. 5) from whence it is circumferentially confined by the wall of the blow gun 34 to form an air blast stream directed at the open mouth of the retort 12. Meanwhile, the charge passing downwardly through the blow box, enters the charge inlet port 52, partially by gravity and partially by suction of the air blast, and is entrained in the air blast stream. Ingress of air from the atmosphere in response to the partial vacuums accompanying the release of the compressed air to form the air blast stream and the entrainment of the charge therein at the

port 52, is provided by the open rear end of the blow gun where inlet pipe 40 enters same and by the openings 54 in housing 24, respectively.

Upon entering port 52, the charge particles have imparted to them a directional velocity tending to approximate that of the air blast stream in which they entrain, which velocity is sufficient, even though the circumferential confinement of the stream be discontinued short of the retort mouth, to carry the charge particles into the retort cavity where they are deposited to form a retort charge of greater density than that resulting from conventional, commercial manual charging methods. The air of the air blast stream is dissipated to the atmosphere at the retort mouth.

As soon as the retort is filled, which will ordinarily be in about one-half of a minute, valve 48 of the top blow gun is turned off and the next valve 48 opened, and so on until all four retorts in that vertical row are charged. Of course, the retorts may be filled in any other order desired, or, a plurality of retorts may be simultaneously charged. In event one or more of the retorts is a bit out of line with the others, as occasionally happens, it is only necessary to adjust the position of the air blast stream for that retort by means of hand wheel 56 or fulcrum unit 82, or both.

During the charging operation, the bucket elevator 26 is in operation to pick up any surplus charge which passes the ports 52 and discharges over baffle 51, through port 53 into the bottom of housing 24, and recirculate the same to the blow box 32.

With the first vertical row of retorts charged, the machine 16 is advanced to the next row and the retorts in that row charged in a similar manner to that heretofore described. This sequence is repeated until all retorts in the furnace are charged. After the machine clears the first few rows of retorts, the condensers (not shown) are affixed at the mouths of the retorts and any spillage of charge cleaned up and recirculated to elevator 26 by way of hopper 64, belt feeder 66 and hopper 70. When the last retorts have been charged the blow box is raised about 8" by turning hand wheel 56, to provide clearance of the condensers by the blow guns 34, and the machine returned on track 14 to the head of the furnace, as is also the overhead feeding device.

While the foregoing illustrates one manner of practicing the invention, it will be understood that various changes and modifications embodying its principles may be made by those skilled in the art within the scope and spirit of the invention as defined by the appended claims. For example, the invention has been described with reference to compressed air to form the air blast stream; however, steam or other gaseous fluids could be used and, hence, in that sense, are to be considered the equivalent of air.

Various of the advantages attending the use of the new process, such as safety of the charger, uniformity of charge throughout the various retorts, ease of charging, etc. are believed already apparent from the description. The following comparison of thirteen consecutive cycles on two furnaces conventionally charged and two furnaces charged in accordance with the invention, will serve to illustrate other advantages afforded by the invention such as increased production as reflected by greater charge density

and enhanced efficiency of the horizontal retort process itself in reducing the zinc of the charge:

	Conven-tion-ally Charged Furnaces	Furnaces Charged by New Process
Lbs. Charged per Cycle, including Blue Powder	48,533	53,808
Lbs. Zn in Charge	29,980	33,611
Recovery in Percent	88.4	89.1
Lbs. Charged as Charge only	43,203	48,885
Lbs. Zinc	26,658	30,526
Recovery (percent) Direct Metal	61.3	63.1
No. of Charge Retorts	288	286
Volume per Retort	2.33	2.33
Lbs. per Charge Retort	150	171
Lbs. Charge per Cu. Ft.	64.3	73.4

10 15

That the use of the invention will consistently result in a retort charge of greater density than that of a retort conventionally charged, is well evidenced by the following table showing the ranges in charge density (lbs. charge per cu. ft. of retort volume) for all charging cycles for all furnaces in four months of regular plant operation:

	Conven-tion-ally Charged Furnaces	Furnaces Charged by New Process
Month "A"	62-69	69-76
Month "B"	62-68	69-77
Month "C"	62-69	66-79
Month "D"	61-69	69-78

In short, even the poorest of the new process charges was the equivalent of the very best of the conventionally charged charges in density, while a comparison of the average charge density for the two methods of charging shows better than 12% greater density for the new process charges.

What is claimed is:

1. A process for charging a horizontal zinc retort which comprises laterally confining a gas stream having a velocity under such confinement capable of entraining charge therein and of imparting to such charge a velocity which will carry it into the retort, directing said confined stream at the open mouth of the retort in substantial registry therewith, entraining a free falling stream of charge particles in the so established gas stream, discontinuing circumferential confinement of the gas stream before it reaches the retort mouth at a point sufficiently spaced from said retort mouth to permit the gas to be liberated to the atmosphere in the space therebetween, the position of said point also being such that the velocity of the entrained charge is sufficient to carry it into the retort cavity and deposit it therein, depositing said charge in the retort, and dissipating the on-coming gas in said stream to the atmosphere in the space between said point and the retort mouth.

2. A process for charging a horizontal zinc retort with zinc bearing material which comprises laterally confining a gas stream, directing said confined stream at the open mouth of the retort in substantial registry therewith, establishing above the gas stream a free falling stream of charge particles, agitating and aerating said free falling stream, directing said stream of particles into said gas stream at substantially a right angle to the path of flow of

the latter, and discontinuing circumferential confinement of the gas stream before it reaches the retort mouth at a point sufficiently spaced from said retort mouth to permit the gas in the stream to be liberated to the atmosphere in the space therebetween, the position of said point also being such that the velocity of the entrained charge is sufficient to carry it into the retort cavity and deposit it therein.

3. A process for charging a horizontal zinc retort with zinc bearing material which comprises so releasing gas under pressure of several tens of pounds per square inch as to effectuate lateral expansion thereof to several times its former volume and confining the released, expanded gas circumferentially but without axial confinement to form a blast stream, directing said confined stream at the open mouth of the retort in substantial registry therewith, establishing above the blast stream a free falling stream of charge particles, agitating and aerating said free falling stream, directing said stream of particles into said blast stream at substantially a right angle to the path of flow of the latter and in the zone in which said lateral expansion of the air is effectuated, conveying away from the blast stream any charge unentrained therein, discontinuing circumferential confinement of the blast stream before it reaches the retort mouth at a point sufficiently spaced from said retort mouth to permit the gas in the stream to be liberated to the atmosphere in the space therebetween, the position of said point being such that the velocity of the entrained charge is sufficient to carry it into the retort cavity and deposit it therein, depositing said charge in the retort, and dissipating the on-coming gas in the gas stream to the atmosphere in the space between said point and the retort mouth.

4. A process for charging a horizontal zinc retort which comprises so releasing gas under pressure of sufficient tens of pounds per square inch as to effect lateral expansion thereof to several times its former volume and confining the released, expanded gas circumferentially to form a blast stream, said stream being directed at the open mouth of the retort in substantial registry therewith, establishing above the blast stream a free falling stream of charge particles, aerating said free falling stream, entraining charge in the so established blast stream by directing said free falling aerated stream of charge particles into said blast stream at a point near but past the latter's source, and discontinuing the circumferential confinement of the blast stream at a point short of the retort mouth where the velocity of the entrained charge is sufficient to carry it into the retort cavity and deposit it therein while the gas in the blast stream is dissipated at the retort mouth.
